UNITED STATES PATENT OFFICE

108,749

DESIGN FOR A RADIO DISPLAY STAND

Robert N. McKinney, Hillside, N. J., assignor to
Philco Radio and Television Corporation, Phil-
adelphia, Pa., a corporation of Delaware

Application June 15, 1937, Serial No. 69,857

Term of patent 14 years

To all whom it may concern:

Be it known that I, Robert N. McKinney, a citizen of the United States, residing in Hillside, Union County, New Jersey, have invented a new, original and ornamental Design for a Radio Display Stand, of which the following is a specification, reference being had to the accompanying drawings, forming part thereof, in which:—

Figure 1 is a perspective view of the radio display stand, showing my design; and

Fig. 2 is an enlarged cross-sectional view thereof taken along line 2—2 of Fig. 1.

I claim:

The ornamental design for a radio display stand, substantially as shown.

ROBERT N. MCKINNEY.
